UNITED STATES PATENT OFFICE.

ROBERT L. HEDGES AND ARTHUR M. BRANCH, OF ST. LOUIS, MISSOURI.

PROTECTIVE COVER FOR BASE-BALL-PLAYING FIELDS AND THE LIKE.

1,063,198.

Specification of Letters Patent.

Patented June 3, 1913.

Application filed March 21, 1912. Serial No. 685,304.

To all whom it may concern:

Be it known that we, ROBERT L. HEDGES and ARTHUR M. BRANCH, citizens of the United States, residing at the city of St. Louis, State of Missouri, have jointly invented certain new and useful Improvements in Protective Covers for Base-Ball-Playing Fields and the Like, of which the following is a specification, reference being had to the accompanying drawings, forming a part hereof.

This invention relates to certain new and useful improvements in protective covers for base-ball playing fields and the like.

As is well known, base-ball fields, and especially the diamond portion thereof, become, after a more or less heavy rain, so soft and wet that it is practically impossible to play ball thereon; consequently, ball-games have heretofore been frequently postponed on account of "wet grounds," resulting in considerable financial loss to the owners or proprietors of such fields. An easily operable and handled protective cover for such fields—a cover which may be quickly and readily placed when required in operative protecting position over the field and afterward easily removed from such position for the playing of a game—has hence been greatly wanted and desired.

The object of our invention is, therefore, broadly to provide a substantially water-proof cover in the form preferably of a large canvas or tarpaulin and supporting and operating means therefor adapted to be readily and easily manipulated when required to operatively support the cover over, and preferably in an inclined position above and away from the surface of, the base-ball diamond and portions of the playing-field adjacent the bases and base-lines, and to afterward remove the cover from such operative position over the field to permit the playing of a game thereupon, the cover when in operative position protecting the covered area from the elements and shedding rain therefrom, thereby maintaining such area or playing field in playing condition and thus obviating the necessity of postponing base-ball games on account of "wet grounds."

With this object in view, our invention resides in the provision of a series or plurality of cover-supporting members, preferably in the form of flexible cables, operatively arranged above the surface of the playing field and adapted to be extended and secured when

required in a preferably downwardly oblique direction over and across the area or playing field to be protected and a cover of flexible material, such as canvas, arranged for movement upon said supporting-members and adapted to be operatively supported thereby when required in open extended position over, and preferably obliquely above, the surface of the area of the playing field to be protected; in the provision on the cover of side and end flaps adapted, when the cover is in open extended or operative position over the area to be protected, to operatively hang down or depend therefrom and thereby prevent at the sides of the cover the entrance of rain onto said area; in the provision of means for folding up or raising such side and end flaps into closed inoperative position; in the provision of cover supporting or raising means, preferably in the form of a series or plurality of cables and winding drums therefor, adapted to quickly raise or remove the cover with its side and end flaps from open extended or operative position over the playing field into folded closed or inoperative position away from or to one side of the playing field; in the provision of simple means for maintaining the supporting-cables in proper operative or extended position for supporting the cover in open extended or operative position over the playing field to be protected; in the provision of means, preferably in the form of winding drums, for readily winding up and removing the supporting-cables from the playing field when the same are not in cover-supporting position; in the provision of means adapted to maintain the supporting-cables taut when extended across the playing field in cover-supporting position; and in the novel construction of the several parts of our new cover and its operating and supporting-means and in the novel arrangement and combination of the same, all as will hereinafter be described and afterward pointed out in the claims.

The flexible cover-supporting-members or cables are shown in the accompanying drawings and will be herein described as extending from a grand-stand across the diamond in lines parallel with the base-lines between home-plate and first-base and between second-base and third-base, but it will be readily understood that said cover-supporting cables may extend in an opposite direction, if desired, or where found convenient; it

will also be understood that, while we have herein shown and will describe our new cover and its supporting and operating means or cables in connection with a grand-
 5 stand, upon which grand-stand the winding drums for the cover-supporting and operating members or cables are operatively mounted and arranged, our new cover and its supporting and operating-means or mem-
 bers may equally well be operatively mounted or arranged on or in connection with any other suitable fixed support or standards. It might also be stated that, while our new protective cover is especially adapted and
 10 designed by us for use in connection with base-ball playing fields, and is herein shown and will be described in that connection, yet it is to be further understood that our new protective cover may be equally well used
 15 in connection with other athletic fields and the like.

In the accompanying drawings, Figure 1 is a side elevational view showing our improved cover in open extended or operative position over a portion of a base-ball playing field and also showing the supporting and operating-means therefor; Fig. 2 is a plan view of the cover and its supporting means in open extended or operative position; Fig. 3 is an enlarged detail sectional view taken approximately on the line 3—3, Fig. 2; Fig. 4 is an enlarged sectional view taken approximately on the line 4—4, Fig. 2; Fig. 5 is a cross-sectional view taken approximately on the line 5—5, Fig. 3; Fig. 6 is a fragmentary front elevational view of a support (in the present instance, a grand-stand) and showing mounted thereon the winding drums for the cover-supporting and raising cables; Fig. 7 is a sectional view taken approximately on the line 7—7, Fig. 6; Fig. 8 is a detail sectional view of one of the supporting-cable anchoring-blocks and the covering-means therefor; Fig. 9 is an elevational view of one of the hangers which are operatively arranged upon and supported by the cover-supporting-cables and to which the lower ends of the cover-raising-cables are fixedly attached and which are adapted to traverse the cover-supporting-cables on the movement of the cover to open extended or operative position and to closed folded or inoperative position; Fig. 10 is a vertical sectional view on the line 10—10, Fig. 9; Fig. 11 is an elevational view of one of the cover-supporting hangers which are also operatively arranged upon and supported by the cover-supporting-cables and which are adapted to likewise traverse the cover-supporting-cables on the movement of the cover to open extended or operative position and to closed folded or inoperative position; Fig. 12 is a vertical sectional view on the line 12—12, Fig. 11; Fig. 13 is an ele-
 65 vational view of one of the hangers to which

the cover guy-wires or cables are attached which are likewise operatively arranged upon and supported by the cover-supporting-cables and also adapted to traverse the cover-supporting cables on the movement of the cover to open extended or operative position and to closed folded or inoperative position; Fig. 14 is a vertical sectional view on the line 14—14, Fig. 13; Fig. 15 is an elevational view of one of the hangers similar to the hanger shown in Fig. 13, but provided with a roller-support and lock for the cover-end-flap elevating ropes; Fig. 16 is a vertical sectional view on the line 16—16, Fig. 15; Fig. 17 is an elevational view of one of the hangers for the cover-side-flap elevating ropes; and Fig. 18 is a vertical sectional view on the line 18—18, Fig. 17.

In the drawings, 1 designates the grand-stand, and arranged and suitably mounted in the upper portion or on the upper deck thereof and located at suitable distances apart, is a series or plurality of winding-drums 2, the shafts of which are each provided with a suitable crank-handle 3 and a ratchet-wheel 4 having a pawl 5 engaging and co-operating therewith. There is preferably one such drum for each one of the cable-supporting members hereinafter described.

Formed in the ground of the playing field somewhat in the rear of the line between first and second-base (or at any other suitable place thereon depending upon the area to be covered and protected), is a row of holes 6 corresponding in number and in alignment with drums 2. Embedded in the ground at the bottom of each of said holes 6 is a block 7 of concrete, metal, or other suitable material, and mounted therein or connected thereto in any suitable manner is a short section of chain or cable 8 carrying at its outer end a preferably swiveled ring 9. When the swiveled rings 9 and their chains are not in use and engaged by the lower ends of the cover-supporting-members or cables hereinafter described, they occupy positions within the upper portions of said holes 6, the said holes being then plugged or covered, as shown particularly in Fig. 8, with removable blocks 10 of rubber or other suitable or analogous material, for obvious purposes.

11 indicates the cover-supporting members, which are preferably, as shown, flexible cables. These cables are fixedly attached at their upper ends to said drums 2—one cable to each drum. The other ends of cables 11 are provided with hooks 12 adapted to engage, when said cables are extended, with said swiveled rings 9, cables 11 being thus when extended operatively held obliquely downwardly across the playing area to be protected. When so in use or extended, cables 11 can be readily drawn taut by the manipulation of the drums 2, and after such

manipulation, such drums can be locked by the engagement of pawls 5 with ratchet-wheels 4, as will be well understood.

Rotatably mounted in suitable bearings 3 preferably below the drums 2, is a shaft 13, and fixed thereon at suitable distances apart and preferably parallel and in alignment with said drums 2, is a series of drums 14—one for each cable 11. Cables 11, when not 10 in use, are adapted to be wound up upon the drums 14 the outer ends of said cables being first disengaged from rings 9 and then brought around to and engaged with suitable rope-ends 16 fastened to said drums 14 15 and provided at their free ends with rings 16^a for receiving said hooks 12. Also rotatably mounted in suitable bearings, preferably arranged above and slightly to the rear of the row of drums 2, is a shaft 17, and 20 fixed thereon in operative position relatively to the drums 2, is a series of drums 18—one for each of the cover-operating or raising members 19. These members 19 are also 25 preferably, as shown, flexible cables. Cables 19 are fixedly attached at their upper ends to said drums 18 and at their opposite ends are provided with and fixedly attached to suitable hangers 20, shown particularly in Figs. 9 and 10, provided with rollers 21 arranged and adapted to ride upon or traverse the corresponding supporting-cable 11. Both shafts 13 and 17 are driven in any suitable manner preferably by means of an electric motor M, as shown. When the cover 30 35 22 hereinafter described is to be raised or drawn from open extended operative or field-protecting position to closed inoperative position, shaft 17 is rotated in the proper direction, whereupon cables 19 will 40 raise or draw said cover, as hereinafter more fully appearing, to one side of the field into closed inoperative position and be wound upon their drums 18.

The cover 22 is preferably of any suitable 45 flexible material or fabric, such as canvas, preferably water-proofed in any suitable manner, and is of such size as to cover or overlie the entire diamond and a considerable area of the playing field immediately adjacent to and outside the various base-lines. As is well known, on practically all base-ball fields, the paths between the bases and such portions of the ground as are usually occupied by the 50 fielders during play are "skinned" or devoid of grass, and it is our intention and purpose to have the cover 22 of such size as to overlie and protect the diamond and this "skinned" portion of the field. 55 Suitably mounted upon and secured to cover 22 is a plurality of parallel rows of suitable hangers 23, shown particularly in Figs. 11 and 12, movably arranged upon, and adapted to support cover 22 from, said 60 cables 11. As will be understood, there is

one row of such hangers 23 for each cable 11, and mounted in and carried by the upper portion of each hanger 23 is a roller 24 arranged and adapted to ride directly upon the corresponding cable 11. And formed 70 through the lower portion of each hanger 23 is an aperture 25 through which the corresponding cover-raising-cable 19 is adapted to freely pass.

Attached to the side edges of the cover 22 75 are flaps or side-walls 26 of canvas or other suitable preferably flexible material or fabric. When cover 22 is in open extended position over the playing area to be protected, these side-flaps 26 are adapted to depend therefrom with their lower edges preferably in contact with or closely adjacent the surface of the ground, as shown particularly in Fig. 5. When the cover 22 is to be raised or drawn from operative position over the 80 field, these side flaps 26 are adapted to be swung inwardly and upwardly against the under side of cover 22—into the position shown by dotted lines in Fig. 5, by means of cords or ropes 27 passing over rollers 28 90 carried by suitable hangers 29, shown particularly in Figs. 17 and 18, secured in proper operative position to and on the under side of cover 22 adjacent its side edges. Each of these rollers 28 preferably gradually increases in diameter toward its ends, as shown particularly in Fig. 17; by such construction the cords or rollers 27, after being pulled over said rollers 28 to elevate said side-flaps, may be shifted laterally in either 95 direction and thereby wedged or locked between the end portions of the rollers 28 and the body of hangers 29 and thus hold said side-flaps 26 in raised inoperative position. When it is desired to again lower the side-flaps 26, said ropes or cords 27 may be easily 100 shifted by a positive pull out of such wedged or locked position, so that they may easily ride on said rollers 28.

Attached at their outer ends to the rear 110 edge of cover 22 is a plurality of guy-lines or ropes 30 corresponding preferably in number to the number of cables 11 and being also preferably arranged respectively in alignment therewith. These guy-lines or 115 ropes 30 have their opposite or upper ends fixedly attached adjacent drums 2 to the grand-stand or other fixed standard and are adapted, when the cover 22 is allowed to run out on cables 11 into open extended or 120 operative position, to determine the distance which the cover 22 is to run out thereupon and to afterward hold or maintain the cover in such position on said cables 11 over the area to be protected. These guy-lines 125 or ropes 30 are preferably supported in operative relation to and from cables 11 by means of suitable hangers 31, shown particularly in Figs. 13 and 14. Each of these hangers 31 is provided in its lower portion 130

with a suitable clamping device 32 adapted to receive and impingly engage with a guy-rope or line 30, as shown particularly in Fig. 13. Each of these hangers 31 is also provided in its upper portion with a roller 33 arranged and adapted to roll upon a cable 11 and thereby maintain said guy-ropes 30 in proper operative relation thereto. Through the center or middle portion of each hanger 31 is formed a suitable aperture 34 for the free passage therethrough of a cover-raising or operating cable 19.

Attached to the rear edge of cover 22 is an end flap 35 preferably of similar fabric or material. When cover 22 is in open extended position over the playing area to be protected, this end flap 35 is also adapted to depend therefrom with its lower edge in contact with or closely adjacent to the surface of the ground, as shown particularly in Fig. 4. When cover 22 is to be raised or drawn from operative position over the field, this end flap 35 is adapted to be swung or raised upwardly and outwardly against said guy-ropes 31, as shown by dotted lines in Fig. 4, by means of elevating ropes or cords 36 attached thereto and passing over and around suitable rollers 37 journaled in depending portions 38 formed on the lower pair of each row, or every other row, as may be desired, of hangers 31. Such hangers are shown particularly in Figs. 15 and 16 and are numbered 31^a. The rollers 37 are substantially similar to rollers 28, and said end flap elevating cords or ropes 36 may similarly, after the end flap 35 has been raised, be shifted laterally in either direction and thereby wedged or locked between the end portion of rollers 37 and the body of hanger portions 38, and flap 35 thus held in raised position. When it is desired to again lower such end flap, ropes or cords 36 may be easily shifted by a positive pull out of such wedged or locked position into a position to easily ride in said rollers 37.

As shown particularly in Fig. 2, our new cover 22, when in operative or field-protecting position, is adapted to cover, and be supported by cables 11 obliquely above and over and away from the surface of, the diamond and portions of the playing field beyond the base-lines, the lower edge of cover 22 being preferably some considerable distance to the rear of the line between first and second base. Thus all rain falling on to cover 22 will naturally drain or run off in one general direction and will discharge upon a portion of the field which is usually covered with grass, seldom traversed by the infielders, and wholly beyond the paths traversed by the base-runners. The side and end flaps 26 and 35 prevent the entrance upon the covered area of rain and wind from the sides of the cover, cover 22 with its said sides and end flaps, when in such operative position,

presenting an appearance somewhat like that of a large tent. To make the said side and end flaps wholly effective for the purpose stated, their lower edges may, if desired, be pinned or anchored to the ground in any suitable manner. 70

When it is desired to remove or raise cover 22 with its said side and end flaps from protecting position over the field, the said side and end flaps are first swung or raised by means of their elevating cords 27 and 36 into inoperative position as before described. Motor M is now operated to properly rotate shaft 17 carrying the drums 18, whereupon cables 19 will be simultaneously wound upon said drums. As said cables 19 are so wound up, the hangers 20 at the lower ends thereof will be drawn upwardly along the cables 11 and engage or contact with the lowermost set of hangers 23. Such set of hangers 23 will in turn be now drawn upwardly along cables 11 with hangers 20 and in turn engage or contact with the next adjacent set of hangers 23. Such latter set of hangers 23 will likewise now be drawn upwardly 80 along cables 11 with hangers 20 and lowermost set of hangers 23, and so on as the cover-raising operation continues, each set of hangers 23 being similarly engaged and drawn upwardly with hangers 20 along 85 cables 11, and during this operation the cover 22 and its side flaps 26 will be automatically folded up into a series of half loops depending from the hangers 23. After the entire cover 22 and said side flaps have 90 thus been folded up, the sets of hangers 31^a will be engaged and likewise moved upwardly along the cables 11 and similarly fold up the said end wall or flap 35, and as the winding up or cover raising operation is continued, the entire cover, with its side and end flaps, and the guy-lines or cables 30 will be drawn upwardly and deposited onto a platform portion of the grand-stand or other suitable support P provided therefor immediately in front of the drums 2 and 18. When this has been accomplished, the drums 2 are now rotated slightly to slacken the cables 11, after which the hooks 12 at the lower ends thereof may be detached from 95 said rings 9, said cables 11 now carried across the field, hooks 12 then attached to the rings 16^a on drums 14, and the motor M operated to rotate the shaft 13 and thereby wind the supporting cables 11 upon said 100 drums 14. The short sections of chains or cables 8 and their swiveled rings 9 are now placed in the holes 6, after which the blocks 10 are positioned therein and the playing field is now ready for use. It will be readily 105 understood that, owing to the fact that the cables 11, when positioned for use, extend obliquely over and across the field, it will be a comparatively easy matter to position the cover over the playing field or diamond 110

whenever required, for after the cover 22 is shifted from its position on the grand-stand or other place of support P and shaft 17 with its drums 18 rotated to permit the unwinding from said drums 18 of said raising-cables 19, cover 22 will, by reason of its own weight and gravity, move freely into open operative position, during such movement the rollers of the various hangers riding smoothly and easily upon the cables 11 and performing in this respect the function of antifriction rollers and the guy-ropes or lines 30 determining the extent of downward travel of cover 22 on its said supporting-cables 11. It will, of course, be understood that, when it is desired to place the cover 22 in operative or protecting position over the field, the supporting cables 11 are first unwound from their drums 14, their hooks 12 operatively attached to said swiveled hooks 9, and said cables then drawn taut by said drums 2.

As it may at times be desirable, particularly in extremely rough weather, to anchor the lower edge of cover 22, hangers 20 are preferably provided with depending eyes 20^a, to which eyes and to said rings 9 any suitable block-and-tackle 39 may be attached when cover 22 is in open operative position. By such means, any slack in cover 22 when open may be taken care of and cover 22 firmly anchored in operative position.

It will be seen that, while our new cover with its supporting and raising means comprises a number of parts, it is comparatively simple, may be easily and quickly lowered into operative position over the field or raised or moved into inoperative position at the side of the field, and when in operative position over the field, freely and thoroughly protects the same from rain or the elements and without injury to the grass-covered portion of the infield.

We do not desire to be limited to the exact details of construction herein shown and described, as we are aware and it is apparent that many changes in size, form, and construction of the various parts of our improved cover and its supporting and operating means may be made and substituted for those herein shown and described without departing from the nature and spirit of our invention.

Having thus described our invention, what we claim and desire to secure by Letters Patent is:

1. The combination with a plurality of independent flexible cover-supporting-members adapted to be extended obliquely over and secured across a base-ball field or the like, of a field-cover of flexible material arranged for movement on and relatively to said supporting-members and adapted to be obliquely supported thereby in operative position over the surface of the field, and

means adapted to move said cover upwardly along said supporting-means into inoperative position; substantially as described.

2. The combination with a plurality of independent flexible cover-supporting-members adapted to be extended obliquely over and secured across a base-ball field or the like, of a field-cover of flexible material arranged for movement on and relatively to said supporting-members and adapted to be obliquely supported thereby in operative position over the surface of the field, said cover being movable by gravity on said supporting-members into operative position, and means adapted to raise said cover upwardly along said supporting members into inoperative position; substantially as described.

3. The combination with a plurality of independent flexible cover-supporting-members adapted to be extended obliquely over and secured across a base-ball field or the like, of a field-cover of flexible material arranged for movement on said supporting members and adapted to be obliquely supported thereby in operative position over the surface of the field, said cover being movable by gravity on said supporting-means into operative position, and means adapted to limit the gravity movement of said cover on said supporting-members into operative position; substantially as described.

4. The combination with a plurality of independent flexible cover-supporting-members adapted to be extended obliquely over and secured across a base-ball field or the like, of a field-cover of flexible material arranged for movement on said supporting-members and adapted to be obliquely supported thereby in operative position over the surface of the field, said cover being movable by gravity on said supporting-members into operative position, means comprising a plurality of independent flexible members adapted to limit the gravity movement of said cover on said supporting-members into operative position, and means including a plurality of flexible members adapted to draw said cover upwardly along said supporting-members into inoperative position; substantially as described.

5. The combination with a support fixedly arranged at the side of a base-ball field or the like, of a plurality of independent flexible cover-supporting-cables engaging at one end with said support and adapted to be extended therefrom over and removably secured across said field, and a field-cover of flexible material arranged for movement on said cables and adapted to be supported thereby in operative position over and away from the surface of the field; substantially as described.

6. The combination with a support fixedly arranged at the side of a base-ball field or

the like, of a plurality of independent flexible cover-supporting-cables engaging at one end with said support and adapted to be extended therefrom obliquely over and removably secured across said field, a field-cover of flexible material arranged for movement on said cables and adapted to be obliquely supported thereby in operative position over the surface of the field, and means adapted to 10 releasably anchor said cables at their free ends; substantially as described.

7. The combination with a support fixedly arranged at the side of a base-ball field or the like, of a plurality of independent flexible cover-supporting-cables engaging at one end with said support and adapted to be extended therefrom obliquely over and removably secured across said field, a field cover of flexible material arranged for movement on 15 said supporting-cables and adapted to be obliquely supported thereby in operative position over the surface of the field, means comprising a plurality of cables adapted to move said cover upwardly along said supporting-cables into inoperative position, and means adapted to releasably anchor said cover-supporting-cables at their free ends; substantially as described.

8. The combination with a support fixedly arranged at the side of a base-ball field or the like, of a plurality of independent flexible cover-supporting-cables engaging at one end with said support and adapted to be extended therefrom obliquely over and removably secured across said field, a field-cover of flexible material arranged for movement on said supporting-cables and adapted to be obliquely supported thereby in operative position over the surface of the field, said cover 30 being movable by gravity on said supporting-cables into operative position, a plurality of guy-ropes attached to said cover and to said support and adapted to limit the gravity movement of said cover on said supporting-cables into operative position, and means adapted to releasably anchor said cover-supporting-cables at their free ends; substantially as described.

9. The combination with a support fixedly arranged at the side of a base-ball field or the like, of a plurality of independent flexible cover-supporting-cables engaging at one end with said support and adapted to be extended obliquely therefrom over and removably secured across said field, a field-cover of flexible material arranged for movement on said supporting-cables and adapted to be obliquely supported thereby in operative position over the surface of the field, said cover being movable by gravity on said supporting-cables into operative position, a plurality of guy-ropes attached to said support and to said cover adapted to limit the movement of said cover on said supporting-cables into operative position,

means comprising a plurality of flexible cables adapted to raise said cover upwardly along said supporting-cables into inoperative position, and means adapted to releasably anchor said cover-supporting-cables at 70 their free ends; substantially as described.

10. The combination with a support fixedly arranged at the side of a base-ball field or the like, of a plurality of independent flexible cover-supporting-cables engaging at 75 one end with said support and adapted to be extended obliquely therefrom over and removably secured across said field, a field-cover of flexible material arranged for movement on said supporting-cables and adapted to be obliquely supported thereby in operative position over the surface of the field, said cover being movable by gravity on said supporting-cables into operative position, a plurality of guy-ropes attached to 80 said support and to said cover adapted to limit the movement of said cover on said supporting-cables into operative position, means comprising a plurality of flexible cables and winding drums adapted to raise said cover upwardly along said supporting-cables into inoperative position, and means adapted to releasably engage with and anchor said cover-supporting-cables at 85 their free ends; substantially as described.

11. The combination with a support fixedly arranged at the side of a base-ball field or the like, of a plurality of independent flexible cover-supporting cables engaging at one end with said support and adapted to be extended obliquely over and releasably secured across said field, a plurality of cover-hangers arranged for rolling movement on each of said cables, a field-cover of flexible material secured to said hangers and movable therewith on said supporting-cables and adapted to be obliquely supported by said supporting-cables in operative position over the surface of the field, said cover with its said hangers being movable by gravity on said supporting-cables into operative position, a plurality of guy-ropes attached to said support and to said cover adapted to limit the movement of said cover on said supporting-cables into operative position, 100 a plurality of guy-ropes attached to said support and to said cover adapted to limit the movement of said cover on said supporting-cables into operative position, means comprising a plurality of flexible cables and winding drums therefor adapted to co-operatively engage with said hangers to raise said cover upwardly along said supporting-cables into inoperative position, and means adapted to releasably engage with and anchor said cover-supporting-cables at 105 their free ends; substantially as described.

12. The combination with a support fixedly arranged at the side of a base-ball field or the like, of a plurality of independent winding drums mounted thereon, a plurality of independent flexible cover-supporting cables attached to said drums and adapted to be extended obliquely therefrom over 110

and releasably secured across said field, a plurality of cover-hangers arranged for rolling movement on each of said cables, a field-cover of flexible material secured to said hangers and movable therewith on said supporting cables and adapted to be obliquely supported by said supporting-cables in operative position over the surface of the field, said cover with its hangers being movable by gravity on said supporting-cables into operative position, a plurality of guy-ropes attached to said support and to said cover adapted to limit the movement of said cover on said supporting-cables into operative position, means comprising a plurality of flexible cables and winding drums therefor adapted to co-operatively engage with said hangers to raise said cover upwardly along said supporting cables into inoperative position, and means adapted to releasably engage with and anchor said cover-supporting-cables at their free ends; substantially as described.

13. The combination with a support fixedly arranged at the side of a base-ball field or the like, of a plurality of winding drums mounted thereon, a plurality of cover-supporting cables attached at one end to said drums and adapted to be extended obliquely therefrom over and across said field, means on the field for engaging with and anchoring said cables at their lower ends, a plurality of cover-hangers arranged for movement on each of said cables, a field-cover of flexible material secured to said hangers and movable therewith on said supporting cables and adapted to be obliquely supported by said supporting-cables in operative position over the surface of the field, said cover with its said hangers being movable by gravity on said supporting cables into operative position, a plurality of guy-ropes attached to said support and to said cover adapted to limit the movement of said cover on said supporting-cables into operative position, and means comprising a plurality of cables and winding drums therefor adapted to co-operatively engage with said hangers to raise said cover upwardly along said supporting-cables into inoperative position; substantially as described.

14. The combination with a support fixedly arranged at the side of a base-ball field or the like, of a plurality of winding drums mounted thereon, a plurality of cover-supporting cables attached at one end to said drums and adapted to be extended obliquely therefrom over and across said field, means on the field for detachably engaging with and anchoring said cables at their lower ends, a plurality of cover-hangers arranged for movement on each of said cables, a field-cover of flexible material secured to said hangers and movable there-

with on said supporting-cables and adapted to be obliquely supported by said supporting-cables in operative position over the surface of the field, said cover with its said hangers being movable by gravity on said supporting-cables into operative position, a plurality of guy-ropes attached to said support and to said cover adapted to limit the movement of said cover on said supporting-cables into operative position, means comprising a plurality of cables and winding drums therefor adapted to co-operatively engage with said hangers to raise said cover upwardly along said supporting cables into inoperative position, and means comprising a plurality of winding drums adapted to wind up said supporting-cables when they are detached from said anchoring means; substantially as described.

15. The combination with a support fixedly arranged adjacent a base-ball field or the like, of a plurality of field-cover supporting-cables engaging at one end with said support and adapted to extend therefrom in an obliquely downward direction across the field, means on the field adapted to engage with said cables at their other end and releasably anchor the same in fixed position across the field, and a field cover supported by, and movable on and relatively to, said cables; substantially as described.

16. The combination with a support fixedly arranged adjacent a base-ball field or the like, of a plurality of field-cover supporting-cables engaging at one end with said support and adapted to extend therefrom in an obliquely downward direction across the field, means on the field adapted to engage with said cables at their other end and releasably anchor the same in fixed position across the field, means adapted to draw said cables taut, and a field cover supported by, and movable on and relatively to, said cables; substantially as described.

17. The combination with a support fixedly arranged adjacent a base-ball field or the like, of a plurality of winding drums arranged on said support, a plurality of field-cover supporting cables having engagement at one end with said drums and adapted to be extended therefrom in an obliquely downward direction across the field, a field-cover arranged upon said cables and adapted to be operatively supported thereby, and means on the field adapted to engage with and anchor said cables at their lower ends; substantially as described.

18. The combination with a support fixedly arranged adjacent a base-ball field or the like, of a plurality of field-cover supporting-cables operatively mounted on said support and adapted to be extended therefrom in an obliquely downward direction across the field, a field-cover arranged upon

- said cables and adapted to be operatively supported thereby, means on the field adapted to detachably engage with and anchor said cables at their lower ends, and means 5 adapted to wind up said cables when their lower ends are detached from said anchoring means; substantially as described.
19. The combination with a support fixedly arranged adjacent a base-ball field 10 or the like, of a plurality of winding drums arranged on said support, a plurality of field-cover-supporting-cables having engagement at one end with said drums and adapted to be extended therefrom in an obliquely downward direction across the field, a field-cover arranged upon said cables and adapted to be operatively supported thereby, means on the field adapted to detachably engage with and anchor said cables at their 15 lower ends, and a plurality of winding drums adapted to wind up said cables when their lower ends are detached from said anchoring means; substantially as described.
20. The combination with a support 25 fixedly arranged adjacent a base-ball field or the like, of a series of independent flexible cables having engagement with said support and extending therefrom over said field, a plurality of hangers arranged for 30 rolling movement on and depending from said cables, and a field-cover of flexible material secured to and carried by said hangers; substantially as described.
21. The combination with a support 35 fixedly arranged adjacent a base-ball field or the like, of a series of independent rolling cables having engagement with said support and adapted to be extended obliquely therefrom over and secured across said field, a plurality of hangers arranged for rolling 40 movement on said cables and adapted to move downwardly thereupon by gravity, a field-cover of flexible material secured to and carried by said hangers, and means 45 adapted to anchor the free ends of said cables; substantially as described.
22. The combination with a support 50 fixedly arranged adjacent a base-ball field or the like, of a series of independent flexible cables having engagement at one end with said support and adapted to be extended obliquely therefrom over and across said field, means on the field adapted to engage with and anchor said cables at their 55 lower ends, a plurality of hangers arranged for rolling movement on said cables and adapted to move downwardly thereupon by gravity, a field-cover of flexible material secured to and carried by said hangers, and 60 means comprising a plurality of cables and winding drums therefor arranged upon said support and adapted to coöperatively engage with said hangers to raise said cover upwardly along said supporting-cables; 65 substantially as described.

23. In a field-cover, the combination with a plurality of cover-supporting members arranged above and away from the surface of the field, of a cover arranged upon and adapted to be supported by said cover-supporting members, a flexible flap attached to said cover and adapted to depend therefrom, and means including a roller on said cover and a cord fixed to said flap and co-operating with said roller adapted to raise said flap inwardly and upwardly against the under side of said cover and to releasably lock the same in such position; substantially as described. 70

24. In a field-cover, the combination with a plurality of cover-supporting members arranged above and away from the surface of the field, of a cover arranged upon and adapted to be supported by said cover-supporting members, a flexible flap attached to said cover and adapted to depend therefrom, a plurality of hangers provided with substantially double cone-shaped rollers attached to said cover, and cords movable on said rollers and engaging with said flap, 80 said cords being adapted to coöperate with said rollers to raise said flap inwardly and upwardly against the under side of said cover and to coöperate with said rollers and hangers to releasably lock said flap in such 85 position; substantially as described. 90

25. In a field-cover, the combination with a plurality of cover-supporting members arranged above and away from the surface of the field, of a cover arranged upon and adapted to be supported by said cover-supporting members, a flexible flap attached to said cover and adapted to depend therefrom, and means including rollers on said cover-supporting members and cords fixed to said flap and coöperating with said rollers adapted to raise said flap upwardly and outwardly away from said cover and to releasably lock the same in such position; substantially as described. 100

26. In a field-cover, the combination with a plurality of cover-supporting members arranged above and away from the surface of the field, of a cover arranged upon and adapted to be supported by said cover-supporting members, a flexible flap attached to said cover and adapted to depend therefrom, a plurality of hangers provided with substantially double coneshaped rollers arranged on said cover-supporting members, and cords movable on said rollers and engaging with said flap, said cords being adapted to coöperate with said rollers to raise said flap upwardly and outwardly away from said cover and to coöperate with 110 said rollers and hangers to releasably lock said flap in such position; substantially as described. 115

27. The combination with a support fixedly arranged adjacent a base-ball field 120

or the like, of a plurality of supporting members having engagement at one end with said support and adapted to be extended therefrom obliquely over and secured across said field, a field-cover arranged for movement on said supporting-members and adapted to be supported thereby obliquely over the surface of said field, flaps at the side and rear edges of said cover adapted to depend therefrom when said cover is in operative position, cords attached to said side flaps and movably engaging with said cover adapted to raise said side flaps upwardly and inwardly into, and to releasably lock the same in, inoperative position, cords having engagement with said end flap and movably engaging with

said supporting-members adapted to raise said end flap upwardly and outwardly into, and to releasably lock the same in, inoperative position, and means comprising a plurality of cables and winding drums therefor adapted to raise said cover with its said side and end flaps upwardly along said supporting-members into inoperative position: substantially as described.

In testimony whereof, we have signed our names to this specification, in the presence of two subscribing witnesses.

ROBERT L. HEDGES.
ARTHUR M. BRANCH.
